(57) **CLAIM**

The ornamental design for an impeller blade for a pump, as shown and described.

DESCRIPTION

FIG. 1 is a front perspective view of an impeller blade for a pump showing the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The design includes a mirror image of the embodiment depicted.

Those portions of the drawings shown in broken lines illustrate environmental features that form no part of the claimed design.

1 Claim, 8 Drawing Sheets
